UNITED STATES PATENT OFFICE.

FRANK STREICH, OF JOLIET, ILLINOIS, ASSIGNOR TO UNION MACHINERY COMPANY,
OF JOLIET, ILLINOIS, A CORPORATION OF ILLINOIS.

WRAPPER AND SEALER FOR BREAD, CARTONS, BOXES, AND THE LIKE.

Application filed October 1, 1921. Serial No. 504,812.

To all whom it may concern:

Be it known that I, FRANK STREICH, a citizen of the United States, and a resident of Joliet, Will County, and State of Illinois, have invented certain new and useful Improvements in Wrappers and Sealers for Bread, Cartons, Boxes, and the like, of which the following is declared to be a full, clear, and exact description.

This invention relates to wrappers and sealers for bread, cartons, boxes and the like, and its principal objects are to provide an apparatus which is automatic in most of its operations; which is simple in construction, easy to operate, and is adjustable to accommodate long and short and high and low loaves of bread, or boxes, cartons and the like, within certain given limits. Another object is to provide a wrapping machine wherein hand levers or foot treadles are dispensed with, whereby the attendant may employ both hands, if necessary in handling the article to be wrapped. Another object is to increase the capacity of devices of this character, whereby a greater numbers of articles may be wrapped within a given time. Another object is to provide a wrapper which may be operated by unskilled persons, and which contains comparatively few moving parts, and is not likely to get out of order. The invention has been designed for use in wrapping and sealing articles with paraffin or wax paper, wherein the paraffin or wax paper is heated after the folds are made to soften the paraffin or wax, after which the latter is permitted to cool, while the flaps are held tightly together, whereby the folded flaps are caused to adhere to each other to make a comparatively tight closure.

The invention consists in the several novel features hereinafter described and claimed.

The invention is clearly illustrated in the accompanying drawings in which:

Fig. 1 is a plan of a wrapper and sealer embodying a simple form of the present invention; Fig. 2 is a side elevation of the flap folding elements of the device; Fig. 3 is a view partly in side elevation and partly in vertical, longitudinal section, showing the front flap folder in a different position from that seen in Fig. 2, the line of section for Fig. 3 being indicated at 3—3 in Fig. 1; Fig. 4 is a front view of one of the front flap folders; Fig. 5 is a view partly in front elevation and partly in vertical cross-section,

taken on line 5—5 of Fig. 2; Fig. 6 is a vertical cross-section taken on line 6—6 of Fig. 1; Fig. 7 is a view partly in front elevation and partly in vertical cross-section, illustrating one of the rear flap folder supports, the line of section being taken at 7—7 in Fig. 1; Figs. 8, 9, 10 and 11 are end views of an article and its wrapper, illustrating the various stages occurring in closing the end of the wrapper; Fig. 12 is a side elevation of a modified form of front flap folder and Fig. 13 is a front view thereof.

Referring first to Figs. 1 to 11 of said drawings, which illustrate a simple embodiment of the invention, the reference characters 15, 15^a designate two parallel, flat table members, that run lengthwise of the machine and form a table upon which the articles are wrapped, and along which they travel from the wrapping elements to the heating and cooling elements. Preferably, said table members 15, 15^a are supported on two crosswise extending bars 16 located under the table members and bolted or otherwise secured to two leg or frame members 17 that extend lengthwise of the table and are fastened to lengthwise extending strips 18. The table member 15 is fixedly secured to the bars 16, as by bolts or nuts, but the table member 15^a rests loosely on said bars 16 and is adjustable toward or away from the table member 15, to accommodate articles of various lengths. The means for effecting the adjustment comprises rack teeth 19 on the bars 16, and spur gears 20, which mesh therewith and are fastened to a shaft or rod 21 journaled in bearing brackets 22 secured to the outer edges of the table member 15^a. A hand wheel 23 at one end of the shaft or rod 21 affords means whereby the shaft or rod may be rotated to adjust the table member 15^a. Bolts 24 (see Fig. 6) extending down from the table member 15^a and through slots 25 in the bars 16, and wing nuts 26 on the bolts, provide means for securing the table member 15^a in any position of adjustment relative to the stationary table member 15.

The present invention has been designed to fold the ends of the wrapper, which has previously been wrapped around the four sides of an article, and both ends of said wrapper are folded back by four separate folds, the front flaps or parts nearest the operator being first folded back against

the ends of the article, after which the rear flaps are folded back upon the front flaps. The bottom end flaps are then folded up and upon the front and rear flaps and finally the 5 top flaps are folded down upon the others. In this condition, the bottom and ends of the wrapper are subjected to heat to soften the paraffin and afterwards removed from the source of heat and permitted to cool 10 while being held in place. It is understood that the wrapper extends beyond the ends of the article therein, and the front, back, bottom and end portions of said projecting ends of the wrapper, I shall term the "front flap," 15 "rear flap," "bottom flap" and "top flap," respectively.

At the front end of the table and mounted thereon are the front flap folders, designated, generally, by the reference character 20 A. Secured to the table beyond said folders A are the rear flap folders B, beyond which are the bottom flap folders C, and following them are the top flap folders D. Upright flap heating plates E and a bottom flap 25 heating plate E¹ are arranged beyond the top flap folder and these heating plates are usually electrically heated. Beyond the heating plates are cooling rolls F and there- 30 beyond, cooling plates G. These several instrumentalities are arranged in pairs (ex- 35 cept the bottom cooling plate), one of each kind being secured to the table member 15 and the other one of each kind being secured to the table member 15^a. The opposing 40 faces of the several parts are arranged in alignment or substantial alignment. The heating plates, cooling rolls and cooling plates are common and well known and re- 45 quire no further description so far as this specification is concerned.

The front flap folders.

The front flap folders A comprise two 45 front flap folding fingers 27 and a depressible finger actuating platform 28 upon which the article to be wrapped is placed in making the first or front flap fold. Each flap folding finger 27 has an arcuate portion 29, which engages with the front flap, a, of 50 the wrapper, A¹, and in one embodiment of the invention, said finger has an arm 30 which is fulcrumed on a pin or shaft 31, which extends into an elongated slot 32 formed in the arm 30 and extending in a 55 direction approximately lengthwise thereof. Each finger 27 stands in a vertical position, parallel with a line running lengthwise of the table, and extends through a vertical slot 33 (see Fig. 4) in a supporting bracket 60 34, which is secured to the front end of the table by screws or the like. The arcuate portion of the flap folding finger 27 is arranged to pass across an end of the article 65 to be wrapped from front to back in folding back the front flap, and the operative con-

nections between the platform and finger for moving it across said end will now be described.

The platform 28 is secured upon the upper ends of two yoke or U-shaped platforms supporting members 35 (see Figs. 1 and 5), each of which is held in an upright position by a pair of levers 36, 37, arranged one above the other and fulcrumed upon the bracket 34 by the pins or shafts 31, 38 which are secured in ears or lugs 39, 40, on said bracket 34 by bolts 41. The arms 36^a, 37^a, of the levers 36, 37, are pivotally connected to the platform supporting member 35 by bolts 42, 42^a. This provides a parallel movement mechanism whereby the platform may be depressed and thereby lowered from the position seen in Fig. 2 to that seen in Fig. 3, while constantly held in a horizontal plane. The front flap folding finger is pivoted to 85 one upright leg 35^a of the platform supporting member, by a bolt 43 which is preferably arranged in axial alignment with the bolt 42^a which connects the lever 37 with 90 said platform supporting member. In order to obtain long bearings for the levers 36, 37, they are formed with stirrup like arms 36^b, 37^b, (see Fig. 4) through which the pins or 95 shafts 31, 38, extend. A coiled tension spring 44 secured to a lug 45 on the lever 36 and to a lug 46 on the table counterbalances the platform and acts to return the parts to normal position after the platform has been depressed and released.

It will be understood that whenever the platform 28 is depressed, the front flap folding finger 27 will be thereby drawn down and forward by the platform supporting member 35, and because of the pin and slot connections 31, 32, said front flap folding finger 27 will be moved forward on the bolt 43 as a fulcrum from the position seen in Fig. 2 to that seen in Fig. 3. It will be observed that the arcuate finger 29 moves over and across the platform 28 on an arc of a circle, struck from the axis of the bolt 42^a, and that said movement across the end of the article to be wrapped is at right angles to the line of fold of the front flap and directly across the end of the article from front to back. The result is that the front flap of the wrapper is folded back and against the end of the article to be wrapped, as is illustrated in Fig. 8.

The platform 28 connects the two platform supporting members 35, whereby the two front flap folding fingers may be actuated simultaneously. The platform may comprise two relatively thin platform members 28^a, 28^b, one lying on the other, and having a connected sliding engagement with each other whereby when the table members 15, 15^a are adjusted relative to each other, the platform members 28^a, 28^b, may adjust themselves accordingly. Conveniently, the

sliding connection between the two members 28^a, 28^b, is made by forming elongated slots 28^c in said members, and by providing head pins 28^d in the members which run in the 5 slots.

The rear flap folders.

The rear flap folders B (see Figs. 2 and 7) comprise horizontally extending plates or 10 strips 46 that run parallel with the table members 15, 15^a, and are set edgewise in a vertical direction. Their forward end portions 47 are bent outwards (see Fig. 1) to engage with the rear flaps, b, of the wrap- 15 per. The rear flap folding plates or strips are made somewhat narrower than the article to be wrapped, in order that they may pass between the top and bottom non-folded flaps, d, c. Each rear flap folding strip is 20 secured to and carried by an arm 48, which extends crosswise of the machine, in a horizontal direction and is formed at its outer end with an enlargement or head 49, in which is a bearing aperture 50 (see Fig. 1), 25 preferably triangular in formation, through which extends a post or standard 51. The post is made triangular in cross-section, so as to conform to the triangular bearing aperture in the head of the arm 48, and a set 30 screw 52 is threaded in said head and bears against one side of the post, thereby holding its other two sides in frictional contact with two sides of the bearing aperture. By partly unscrewing the set screw 52, the 35 arm and therewith the rear flap folding strip may be raised or lowered to accommodate high or low articles to be wrapped. The post is formed with flanges 53 that engage the edge and bottom of the table and it 40 may be held in place on the table by bolts and wing nuts 54, as shown. The rear flap folding strips engage and bend the rear flaps, b, back on the folded front flaps, a, as the article is moved past them, and 45 said flaps, a, b, are thereby held in folded position to and until the bottom flap folders have commenced their folding action.

The bottom flap folders.

50 The bottom flap folders C may comprise upright flat portions 55, which extend lengthwise of the table members 15, 15^a, close to and at the outer sides of the rear flap folding strips 46. Said bottom flap 55 folders are secured to the table members 15, 15^a, by bolts or screws 56, that extend through transverse slots in flanges 57, that are formed on the lower edges of the bottom flap folders 55. The slots permit of adjustment of the bottom flap folders laterally or transversely of the table.

55 The upper edge of each bottom flap folder is in the form of a reverse curve, starting at the forward end of the bottom, and ending near the rear end of the top (see Fig. 2).

Said edge engages the bottom flap c and folds it upward against the other folded flaps, a, b, as the article is pushed between the bottom flap folders, and it holds the folded flaps in folded condition until the top 70 flap folder has commenced its action.

The top flap folder.

The top flap folders, D, comprise upright, flat, flap folding plates 58, which 75 extend parallel with the table members. The lower edges 59 of the plates 58 are inclined downwardly from front to back and their rear end portions 59^a are curved down more abruptly than the forward portions. Each flap folding plate 58 is secured to a crosswise extending strut 60 by screws or the like, and said strut is adjustably supported on a post or standard 61 which is secured to and extends up from a table member. Conveniently, the strut may be guided between two vertically extending ribs 62 of the post 61 and clamp screws 63 are provided, which bear against the outer face of the post and have threaded stems 80 that extend through a vertical slot 64 in the standard and are threadedly secured in the strut 60. The flap folding plates 58 may be adjusted in a vertical direction to accommodate high or low articles, by partially unscrewing the clamp screws 63. The lower inclined edges of the flap folding plates 58 engage the top flaps, d, when the article is pushed under them and fold said top flaps 85 down on the others and hold all of the flaps in folded position until the wrapped article is pushed back between and over the heating plates E, E¹.

Operation.

105

In the operation of the device, the loaf of bread or the other articles to be wrapped, is first placed on the wrapper A¹, and the latter wrapped around the sides thereof, 110 forming a tube having end portions projecting beyond the article. In this condition the attendant places the article on the platform behind the upper ends of the brackets 34, which act as guides for the article. The loaf or other article is carefully positioned on the platform, so as to come between the front end of the front flap folding fingers, and it is then pressed in a downward and forward direction away from the attendant, 115 thereby depressing the platform 28 and therewith the parallel movement levers 36, 37, until the platform strikes the table, after which the attendant pushes the article past the rear, bottom and top flap folders, and 120 leaves it standing between and over the heating plates E, E¹. The downward movement of the platform is translated into a movement of the front flap folding fingers across the ends of the article, in planes approximately at right angles to the folding 125

130

lines of the front flaps, through the instrumentality of the brackets 35, to which the fingers 27 are pivotally connected, and the pin and slot connections 31, 32, between the brackets 34 and fingers 27. When the article is slid from the platform, the springs counterbalance the weight of the platform and return it to its upper position and thereby returning the fingers to inactive position.

10 In the modified form illustrated in Figs. 12 and 13, the depressible platform 28 is supported by yoke like supports 35^c, and its movement is controlled by the parallel movement levers 36^c connected to the supports 35^c, as in the preferred form, and a counterbalancing spring 44^c attached to one of the levers may be used for returning the parts to inactive position. The front flap folders 27^c are movable across the ends 15 of the article to be wrapped in planes at right angles to the folding line of the front flaps, and the mechanism for translating the up and down movements of the platform into said movements of the front 20 flap folding fingers across the ends of the article to be wrapped, comprises a toothed rack 30^c, supported by the bracket 34^c, a pinion 30^d rotatively mounted on the support 35^c; a second pinion 30^e fixedly connected to the pinion 30^d and a toothed rack 30^g secured to the finger 27^c and meshing with the pinion 30^d. The toothed rack 30^g is slidably guided in a grooved guide member 30^h secured to the lower side of the platform. 25 30

35 In operation, when the platform is depressed, the pinion 30^a is carried down in mesh with the rack 30^c and is thereby rotated; consequently the pinion 30^f is rotated and the rack 30^g and therewith the finger 27^c is moved forward. The latter passes across the end of the article supported by the platform in a plane at right angles to the folding line of the front flap.

45 The springs are preferably of sufficient tension to hold the platform in its upper position, so that when a loaf of bread, or other article is placed on the platform, very little effort is required to depress it.

50 Figs. 8, 9, 10 and 11 illustrate the several folds made by the flap folders. Fig. 8 shows a fragment of the first flap folding finger in dotted lines across the folded front flap; Fig. 9 shows the rear flap folded down under the rear flap folder; Fig. 10
55 shows the bottom flap folded up against the other folded ones, and Fig. 11 shows the top flap folded down over the others. The several flap folders are illustrated in dotted lines in these four figures to show
60 their action on the flaps.

More or less variation of the exact details of construction is possible without departing from the spirit of this invention; I desire, therefore, not to limit myself to the exact form of the construction shown

and described, but intend, in the following claims, to point out all of the invention disclosed herein.

I claim as new and desire to secure by Letters Patent:

1. In a device for wrapping articles, the combination of a counterbalanced, depressible platform for receiving the article, a flap folding finger movable with said platform, and finger actuating members operated by said platform. 75

2. In a device for wrapping articles, the combination of a counterbalanced, depressible platform for receiving the article, and movable from an upper to a lower position, a flap folding finger, movable transversely across an end of said article in a plane approximately at right angles to the line upon which the flap is folded, and operative connections between said platform and finger, for translating the downward movement of said platform into said transverse movement of said finger. 80 85

3. In a device for wrapping articles, the combination of a counterbalanced, depressible platform for receiving the article, a flap folding finger movable with said platform, and across the end of said article, and operative connections between said platform and finger, for translating downward movement of said platform into movement of the finger across the end of said article. 90 95

4. In a device for wrapping articles, the combination of a counterbalanced, depressible platform for receiving the article, a reciprocating flap folding finger, movable in its own plane across the end of the article, and finger reciprocating means operatively connecting said platform with said finger. 100

5. In a device for wrapping articles, the combination of a counterbalanced, depressible platform for receiving the article, a reciprocating flap folding finger, movable in its own plane across the end of the article, means for guiding said finger to move in a plane approximately at right angles to the line upon which the flap is folded, and finger reciprocating means operatively connecting said platform with said finger. 105 110

6. In a device for wrapping articles, the combination of a counterbalanced, depressible platform for receiving the article, an oscillatory flap folding finger, movable in its own plane across the end of the article, and finger oscillating means operatively connecting said platform with said finger. 120

7. In a device for wrapping articles, the combination of a counterbalanced, oscillatory platform upon which the article is received, parallel movement members connected to said platform and arranged to maintain it in horizontal position, a flap folding finger movable with said platform, and finger actuating members operated by said platform. 130

8. In a device for wrapping articles, the combination of a counterbalanced, oscillatory platform upon which the article is received, parallel movement members connected to said platform and arranged to maintain it in horizontal position, a flap folding finger, movable transversely across an end of said article in a plane approximate'y at right angles to the line upon which 10 the flap is folded, and operative connections between said platform and finger, for translating the downward movement of said platform into said transverse movement of said finger.

15 9. In a device for wrapping articles, the combination of a counterbalanced, oscillatory platform upon which the article is received, parallel movement members connected to said platform and arranged to maintain it in horizontal position, a flap folding finger movable with said platform, and across the end of said article, and operative connections between said platform and finger for translating downward movement 20 of said platform into movement of the finger across the end of said article.

10. In a device for wrapping articles, the combination of a counterbalanced, oscillatory platform upon which the article is received, parallel movement members connected to said platform and arranged to maintain it in horizontal position, a reciprocating flap folding finger, movable in its own plane across the end of the article, and 35 finger reciprocating means operatively connecting said platform with said finger.

11. In a device for wrapping articles, the combination of a counterbalanced oscillatory platform upon which the article is received, parallel movement members connected to said platform and arranged to maintain it in horizontal position, a reciprocating flap folding finger, movable in its own plane across the end of the article, 45 means for guiding said finger to move in a plane approximately at right angles to the line upon which the flap is folded, and finger reciprocating means operatively connecting said platform with said finger.

50 12. In a device for wrapping articles, the combination of a counterbalanced, oscillatory platform upon which the article is received, parallel movement members connected to said platform and arranged to maintain it in horizontal position, an oscillatory flap folding finger, movable in its own plane across the end of the article, and finger oscillating means operatively connecting said platform with said finger.

60 13. In a device for wrapping articles, the combination of a counterbalanced, depressible platform, a pair of parallel movement members connected to said platform, and movable in a vertical direction, an oscillatory flap folding finger connected there-

with to move in its own plane with said platform, across an end of the article thereon.

14. In a device for wrapping articles, the combination of a depressible platform upon 70 which the article is received, a pair of oppositely disposed flap folding fingers movable with said platform, and finger actuating mechanism operated by said platform, one finger and its actuating mechanism being 75 adjustable toward and away from the other finger and its actuating mechanism.

15. In a device for wrapping articles, the combination of a pair of adjustably connected table members, a depressible platform upon which the article is received, a pair of oppositely disposed flap folding fingers movable with said platform, and finger actuating members carried by said 80 table members, operated by said platform, 85 one finger and its actuating member being adjustable toward and away from the other finger and its actuating member.

16. In a device for wrapping articles, a depressible, extensible platform upon which 90 the article is received, a pair of oppositely disposed, oscillatory flap folding fingers, and parallel movement finger actuating members, operated by said platform, one finger and its actuating members being adjustable 95 toward the other finger and its actuating members.

17. In a device for wrapping articles, a depressible platform upon which the article is received, a pair of oppositely disposed, oscillatory flap folding fingers movable with said platform, a pair of supporting members for said platform, parallel movement finger actuating members, 100 one pair for each finger, pivotally connected 105 to said platform supporting member, and means for guiding said fingers to move in their own planes across the ends of said article, one finger and its finger actuating member being adjustable toward and away 110 from the other finger and its actuating member.

18. In a device for wrapping articles, a depressible platform upon which the article is received, a pair of oppositely disposed, oscillatory flap folding fingers movable with said platform, a pair of supporting members for said platform, parallel movement finger actuating members, one pair for each finger, pivotally connected to 115 said platform supporting member, and means, including a stationary pin, and a slot in the finger, one edge of which rides on the pin, for guiding said fingers to move 120 in their own planes across the ends of said article, one finger and its finger actuating members being adjustable toward and away 125 from the other finger and its actuating members.
